O. E. HUEBNER,
STARTING AND IGNITION SYSTEM.
APPLICATION FILED JAN. 8, 1919.

1,361,259.

Patented Dec. 7, 1920.

UNITED STATES PATENT OFFICE.

OTTO E. HUEBNER, OF TOLEDO, OHIO, ASSIGNOR TO INDUSTRIAL RESEARCH CORPORATION, OF TOLEDO, OHIO, A CORPORATION OF DELAWARE.

STARTING AND IGNITION SYSTEM.

1,361,259.

Specification of Letters Patent.

Patented Dec. 7, 1920.

Application filed January 8, 1919. Serial No. 270,224.

To all whom it may concern:

Be it known that I, Otto E. HUEBNER, residing at Toledo, in the county of Lucas and the State of Ohio, have invented certain new and useful Improvements in Starting and Ignition Systems, of which I declare the following to be a full, clear, and exact description.

This invention relates to improvements in ignition systems for gas engines, and consists principally in automatic means for increasing the permeability of the field of the induction coil whereby the mutual inductance of the primary and secondary windings is increased, thus increasing the electromotive force induced in the secondary and improving the sparks produced in the spark plug. The invention here described and claimed constitutes an improvement on that disclosed in my copending application, Serial Number 270,684, filed January 11, 1919.

So far as I am aware, induction coils for gas engine ignition systems heretofore have been built with fixed amounts of metal in the magnetic paths. At starting and at low speeds, a magnetic path of considerable permeability is desirable in order that there may be a large inductance, the time increment between each make and break in the primary circuit being sufficient to permit the current to approach more or less closely the maximum value possible. At high engine speeds the time increment referred to is much smaller, and consequently it is desirable to reduce the permeability of the magnetic path of the coil in order to reduce the lag in the current and give it an opportunity to build up. Because of these conditions a coil built for maximum efficiency at starting will be unsatisfactory for average and high speed running and one built for maximum efficiency at high engine speeds produces an unsatisfactory spark at starting.

It is the principal object of my invention to provide a coil which is capable of giving something near the maximum efficiency both at starting and at high engine speeds. Another object of the invention is the provision of means for increasing the permeability of the field of an induction coil used for ignition purposes, which means shall be brought into play automatically whenever the engine is running at a low

speed and shall be rendered inoperative whenever the engine speed increases beyond a predetermined point.

A further object of the invention is the provision of such an automatic control without the use of additional electromagnets, or other electrical apparatus, the electromagnetic function of the ignition coil itself being utilized to accomplish the purpose.

Other objects and objects relating to details of construction and economies of manufacture will appear as I proceed with the description of that embodiment of the invention which, for the purposes of the present application, I have illustrated in the accompanying drawing, in which:

Figure I is a diagrammatic view illustrating the application of my invention to a gas engine provided with an electric starting motor.

Fig. II is a top plan view of the ignition coil and shell therefor in the inoperative position.

Fig. III is a vertical cross-section on the line III—III, Fig. II.

Fig. IV is a diagrammatic view of a modified form of induction coil embodying my invention.

Similar reference characters refer to similar parts throughout the different views.

In the drawing the numeral 10 represents an ignition coil having a primary winding connected to the circuit wires 11 and 12 in which are connected also a battery 13 or other source of current, a switch 14 and a current interrupter 15. The latter is driven by a cam 16, mounted upon the cam shaft of the engine, and adapted to make and break connection four times for each revolution, it being assumed for purposes of illustration that the engine is a four cylinder one. A condenser 17 is arranged in parallel with the interrupter to decrease sparking. The secondary winding of the ignition coil is connected at one end to a current distributor 18, and at the other end to the ground, the spark plugs of the engine being diagrammatically indicated at 19.

In one form of my invention, there is secured to the upper end of the spool of the ignition coil, a plate 20 which carries two arms 21 upon which are pivoted at 22 the two halves 23 of a metallic shell. Although I have shown the shell in two parts only, it is obviously fully within the realm of the

- invention to sub-divide the shell into any desired number of parts. The parts 23 of the shell are held normally away from the coil by springs 24. As will be obvious, when sufficient electro-magnetic effect is produced by the passage of a current through the coil 10, the shell parts 23 will be attracted toward the coil against the action of the springs 24.
- 10 In Fig. IV I have illustrated a modification in which the coil is not provided with a shell but has a core 25 which is slidable within the coil. The coil casing 26 has mounted upon its upper end a yoke 27 supporting a spring 28 which tends to hold the core 25 part way out of the coil in the position illustrated in the drawing. However, when the electro-magnetic effect of the coil is sufficiently increased by the action of a 20 strong current through its primary winding, the tension of the spring 28 is overcome and the core is drawn down into the coil, thereby increasing the permeability of its field.
- 25 In Fig. I there is illustrated diagrammatically, in addition to the ignition system, a starting motor and a dynamo with their electrical connections. 29 represents the motor and 30 the dynamo. 31 is a switch by means of which the starting motor is set in operation, drawing current from the battery 13. When sufficient engine speed is attained, the shunt 32 of the cut-out magnet 33 will be energized enough to cause 35 the magnet to attract its armature 34 whereupon current passes from the third brush 35 of the dynamo through the field 36, the series coil 37 of the cut-out, through the closed switch 14, interrupter 15, wire 11, 40 primary of the induction coil, wire 12 and wire 38 back to the dynamo.
- The operation of my invention is automatic. At starting and at low running speeds, current from the battery 13 is strong enough to energize the induction coil as an electro-magnet to attract the shell parts 23 or core 25, as the case may be, thus bringing more metal into the path of the magnetic lines of force of the coil, increasing 50 the inductance and hence the electromotive force induced in the secondary winding, thereby producing hotter sparks in the spark plugs of the engine. At high engine speeds this same amount of metal in the 55 magnetic path is undesirable, since it increases the current lag. At low speed there is sufficient time between each successive make and break in the primary circuit to permit the current to build up in spite of 60 the lag, but this is not true at high engine speeds, for the time increment between make and break is then much smaller. When a higher speed is reached, the shell or core being in the inner position, the lag is so 65 great that the surges of current in the pri-

mary winding do not attain an amperage sufficient to longer overcome the tension of the spring 24 or 28, as the case may be, and the shell or core thereupon moves to its outer position, whereupon the current lag is somewhat reduced and the current somewhat increased, though not enough to again attract the shell or core until the engine speed is reduced.

I am aware that the particular embodiment of my invention above described and illustrated in the accompanying drawing is susceptible of considerable variation without departing from the spirit thereof, and, therefore, I desire to claim my invention broadly as well as specifically, as indicated by the appended claims.

I claim as my invention:

1. In an ignition system for gas engines, an induction coil, and means for increasing the magnetic permeability of the field of said coil, said means being automatically put into operation when the magnetic field of the coil exceeds a predetermined density.

2. In an ignition system for gas engines, an induction coil, and means for increasing the magnetic permeability of the field of said coil, said means being automatically put into operation when the magnetic field of the coil exceeds a predetermined density and automatically thrown out of operation when the magnetic field falls below the aforesaid density.

3. In an ignition system for gas engines an induction coil, a metallic, magnetic conductor for said coil, and resilient means for holding said magnetic conductor out of the shortest magnetic path, said means being proportioned to yield to the magnetic attraction of the coil for the magnetic conductor during the passage through the coil of a current of predetermined strength.

4. In an ignition system for gas engines, an induction coil, a metallic, magnetic conductor for said coil resiliently held out of the shortest magnetic path, the current through said coil at low engine speeds energizing said coil sufficiently to draw said magnetic conductor toward the shortest magnetic path.

5. In an ignition system for gas engines, an induction coil, a metallic shell therefor, means tending to move said shell away from the coil, said coil being proportioned to attract said shell against the action of said means during the passage through the coil of a current of predetermined strength.

6. In an ignition system for gas engines, an induction coil, a pivoted metallic shell therefor, means tending to swing said shell away from the coil, said coil being proportioned to attract said shell against the action of said means during the passage through the coil of a current of predetermined strength.

7. In an ignition system for gas engines, an induction coil, a divided shell therefor, means tending to move the parts of said shell away from the coil, said coil being proportioned to attract said shell parts against the action of said means during the passage through the coil of a current of predetermined strength.

8. In an ignition system for gas engines, 10 an induction coil, a shell therefor divided longitudinally into a plurality of parts, means tending to move said parts away from the coil, said coil being proportioned to attract said shell parts against the action of said means during the passage through

the coil of a current of predetermined strength.

9. In an ignition system, an induction coil, a shell therefor divided longitudinally into a plurality of parts, means tending to move said parts away from the coil, a current source and a current interrupter in circuit with said coil, the current passing at low engine speeds energizing the coil sufficiently to attract said shell parts toward the coil against the action of said means.

In testimony whereof, I affix my signature.

OTTO E. HUEBNER.
